UNITED STATES PATENT OFFICE

EDWEY Z. WAINWRIGHT, JR., OF PITTSBURGH, PENNSYLVANIA

AUTOMOBILE SIGNAL

Application filed May 28, 1929. Serial No. 366,584.

This invention relates to an improvement in illuminated signals, and particularly those for use on an automobile to indicate when and in which direction the vehicle is to be turned.

Various signal devices have been employed in the past, some of which have included the combination of a tail-light, a stop-light and directional indices. In devices of this kind, however, it is desirable that warning indication be given before a directional index is displayed. That is to say, it is desirable to give notice several hundred feet before turning, and if a directional index is displayed this far away from the turning point, it loses its significance, or is disregarded and forgotten by the following drivers. Therefore, an auxiliary warning is desirable prior to the final indication.

20 The object of the present invention is to provide a directional signal device for automobiles, which has auxiliary warning lights arranged to be displayed prior to the operation of the directional signal.

25 A further object of the invention is to provide a directional signal device having an auxiliary warning light arranged to be displayed prior to the operation of the directional signal, and to provide means whereby 30 the auxiliary warning light may function as a tail light.

In the accompanying drawings Fig. I is a view in front elevation of the signal device of the present invention; Fig. II is a view in 35 front elevation of the body member of the device showing the front plate and the glass members removed from in front of the light bulbs; Fig. III is a bottom view of the device, to larger scale, and partially in elevation and partially in section; and Fig. IV is a diagrammatic view, indicating the electrical wiring scheme. Figs. V and VI are views corresponding to Figs. I and II re-

40 spectively, showing the tail-light to larger scale and with slightly different dimensional proportions; the light bulbs, however, are not shown in their sockets in Fig. VI.

45 Referring to the drawing, the numeral 1 designates the body member of the device, 50 which is preferably formed integrally of

aluminum. Inset from the front surface 3 of the member are a plurality of reflector chambers in which the light bulbs 2 are operatively mounted. Chambers 4 and 5 and their included light bulbs serve to illuminate 55 respectively the lens of the stop-light 6 and tail-light 7. Similarly, the chambers 8 and 9 may in conjunction with their light bulbs illuminate the auxiliary warning lens 10 and 11, and the lights in chambers 12 and 13 may 60 enlighten the arrow indices 14 and 15.

As may be seen in Fig. III, a front cover plate 16 serves in conjunction with a backing plate 17 to retain the lens or glass members in appropriate position before the several light chambers. Obviously these plate members are suitably stenciled for this purpose. The lower or under wall 30 of the member 1 is discontinued along the edges 31, and grooves 32 are provided adjacent those edges to receive a glass or transparent plate to serve as a central bottom closure for the member 1. The rear cover plate 33 maintains the transparent plate in the desired position in the grooves.

75 The purpose of forming a portion of the bottom of the member 1 of transparent material is to permit light from the electric bulb in the downwardly open chamber 5 to illuminate the license plate (not shown) 80 which is normally affixed to the flange 34 of cover 33. It should be noted that the chambers 8 and 9 of the warning lights 10 and 11 are also formed to open downwardly, and the importance of this will presently be described.

85 The lights 2 within the member 1 have their positive electric terminals grounded through the said member. The electrical connections 40 and 41 pass from the negative terminals of the stop and tail light bulbs respectively to the usual operative connections and switches within the car.

90 The auxiliary switch, indicated by the numeral 42, has four contact points 43, 44, 45 and 46. By means of wires 47, the negative terminals of the bulbs of both of the warning lights 10 and 11 are connected to both of the contact points 44 and 45. The wire 48 connects the negative terminal of the bulb behind 95

the arrow 14 to the contact 43, and the wire 49 similarly connects the bulb behind the arrow 15 to the contact 46.

wardly to afford illumination of a license plate, substantially as described.

In witness whereof, I hereunto set my hand.

EDWEY Z. WAINWRIGHT, JR. 70

When the driver of the car to which my device is attached wishes to make a left turn, he moves the electrically conductive switch-handle 50 into contact with point 44. (This should be done when the car is several hundred feet away from the point of turning.)

10 An electrical circuit will obviously be closed through the bulbs of the two warning lights 10 and 11, and these lights will glow to attract the attention of the drivers of the following cars. As the car nears the turning point, the handle 50 is swung into contact with the point 43, and the directional index 14 will be displayed, unmistakably indicating at the proper moment that a left turn is about to be made. In making a right turn the operation 15 of the handle 50 will be to the right in a manner similar to that described in making a left turn.

It is well known that many accidents are caused at night due to the fact that drivers 20 proceed without tail-lights showing on their cars. Often the tail-light fails on the road, and there are no facilities available for its immediate repair. To prevent the danger arising from such a contingency, the present 25 invention lends itself. As mentioned above, the chambers 8 and 9 of the warning lights open downwardly, and should for any cause the normal tail-light 7 fail, the switch handle may be positioned in contact with either of 30 the points 44 or 45. The two light bulbs within the chambers 8 and 9 may then remain glowing (or one of them in case the other thereof has failed) to illuminate the license plate, and serve generally instead of the central tail-light 7.

10 I claim as my invention:

1. An automobile signal device comprising an integral body member, said body member being formed with a plurality of light-reflecting chambers, an electric bulb in each of said chambers, two oppositely pointing directional indices arranged one in front of each of two of said chambers, a tail-light 15 located medially of said indices and arranged in front of another of said chambers, an auxiliary tail light associated with each directional index and each of such auxiliary lights being arranged severally in front of two other 20 of said chambers, and means for effecting the illumination of the bulbs in the chambers to the rear of each of said auxiliary tail lights and said indices, which means are adapted to cause the illumination of one or the other 25 of said indices only after the illumination of its associated auxiliary tail light.

2. The structure of the next preceding claim, in which each chamber to the rear of the auxiliary tail lights as well as the chamber to the rear of the tail light opens down-
